UNITED STATES PATENT OFFICE.

JOSEPH R. PALMENBERG, OF NEW YORK, N. Y.

DESIGN FOR A HAT AND COAT RACK.

SPECIFICATION forming part of Design No. 14,310, dated September 18, 1883.

Application filed July 31, 1883. Term of patent 14 years.

To all whom it may concern:

Be it known that I, JOSEPH R. PALMENBERG, of the city of New York, county and State of New York, have invented a new and original Design for a Hat and Coat Rack, of which the following specification is a full, clear, and exact description, reference being had to the accompanying drawing, forming part of this specification.

10 The drawing represents a perspective view of my newly-designed hat and coat rack.

My hat and coat rack consists of a spherical block or ball, *a*, having an arm, *b*, for attachment to a wall or other support. To this ball 15 are secured upwardly-extending curved rods *c*, two of said rods having ornamental shoulders *d*. To the ball *a* are also attached short

downwardly-projecting hooks *e*, as shown. *f* is an ornamental tip or projection on ball *a*.

I claim as my invention—

1. The design for a hat and coat rack, consisting of ball *a*, arm *b*, rods *c*, and hooks *e*, as described and shown.

2. The design for a hat and coat rack, consisting of ball *a*, arm *b*, rods *c*, having shoulders *d*, and of hooks *e*, as described and shown.

3. The design for a hat and coat-rack, consisting of ball *a*, arm *b*, rods *c*, hooks *e*, and tip *f*, as described and shown.

J. R. PALMENBERG.
